DROP PIT APPARATUS

Louis D. Holmes, Blue Island, and Robert S. Hammon, Winnetka, Ill., assignors to Whiting Corporation, a corporation of Illinois

Application January 14, 1950, Serial No. 138,678

9 Claims. (Cl. 104—32)

1

Our invention is directed to drop table apparatus, particularly of the type employed in a pit extending transversely beneath a series of railroad tracks and utilized for raising and lowering tops which bridge the pit.

Drop table installations are widely employed in railroad shops where it is frequently necessary to exchange trucks, axle assemblies, or the like on railway vehicles. These installations usually include one or more service tracks extending laterally with respect to a transverse pit and bridged by suitable service track tops releasably anchored to the pit walls. In instances of this type, a drop table is mounted for movement upon rails extending longitudinally along the pit bottom and is provided with a lifting platform movable upwardly into engagement with the various tops spanning the pit. When a vehicle is to be serviced, as by removal of a truck, it is moved along the service track rails until the truck to be removed is disposed on the service track top. The drop table apparatus is then usually brought into position below the top, the top disengaged from the pit walls, and the top and vehicle raised slightly by the drop table apparatus, which permits engagement of the body of the vehicle by suitable body supports disposed near the top. The table and top are then lowered so that the truck or wheel assembly can be disengaged and subsequently lowered while in position on the top into the pit by the drop table. The table is then moved laterally along the pit and subsequently elevated until the rails on the top are in alignment with the rails of a suitable release track or storage pit on to which the wheels or trucks are to be discharged. Similar usage is made of the apparatus for other purposes, such as repair or replacement of springs or other running gear associated with the vehicle.

In the past, considerable difficulty has been experienced in handling the release track top which bridges the pit along the release track. In some instances it has been customary to first lower the release track top on the drop table and then nest the service track top upon the release track top, thus permitting the truck on the service track top to be elevated together with the top to the level of the release track, and there discharged on to the release track proper. This nesting of the tops requires a deep pit, as well as a heavier drop table apparatus, and consumes a substantial amount of time.

Another expedient sometimes employed is to lift the release table top from its position across the pit by an overhead crane, thus permitting

the drop table to elevate a service track top to the release track level. This is a time-consuming, relatively hazardous operation and requires the services of a suitable overhead crane for a considerable period of time.

A third expedient sometimes employed is to hinge the release track top at one end so that its opposite end may be raised with suitable hoisting equipment. While this permits elevation of a service track top to the level of the release track rails, travel is blocked in one direction on the release track and all material formerly disposed on the release track top must be removed prior to raising the top. Failure of rope and hoisting equipment makes such an operation hazardous to the workmen and in addition consumes appreciable time.

In other installations, four heavy posts are manually placed in suitable sockets disposed on the lifting platform of the drop table in position to engage the under side of the release track top. As the platform is raised carrying with it the service track top, the release track top is carried upwardly on the posts, thus permitting the service track top to reach release track level. These posts must, however, be removed from the drop table before the release track top can be lowered below release track level or before the drop table can be moved longitudinally along the pit. It is therefore necessary to repeat the operation frequently. Several workmen are of course required to perform this operation, which consumes considerable time and is becoming increasingly more difficult as the size and weight of table tops increase. Furthermore, the posts, which are usually carried on the drop table apparatus, may interfere with the movement of trucks or axle assemblies on to and off of the table.

One of the most important objects of our invention is to overcome the above-mentioned and other disadvantages of prior art devices through the provision of a drop table installation which will automatically elevate a release track top when the lifting platform of the drop table is raised from below the release track top.

Another primary object of our invention is to provide a drop table installation in which the upward movement of the lifting platform of a drop table beneath the release track top will elevate the top only when a service track top is carried on the lifting platform.

Other important objects include the provision of a drop table apparatus which requires only a relatively shallow pit, which may be operated by a single workman located either at a remote point

or at the table, and which inherently prevents the unintentional nesting of tops upon the lifting platform of the drop table.

Further objects of our invention, as well as the details of construction or our preferred embodiment and its many advantages, will be disclosed in the following description of our invention and in the appended drawings, in which:

Fig. 1 is a diagrammatic plan view of a typical drop table installation;

Fig. 2 is a diagrammatic elevation of the arrangement shown in Fig. 1;

Fig. 3 is a diagrammatic partial elevation of a drop table in position below a release track top;

Fig. 4 is a partial diagrammatic elevation of a drop table operating without a top on a lifting platform;

Fig. 5 is a partial cross section through one of our vertical posts;

Fig. 6 is a partial diagrammatic elevation of our device in operation with a top in position on a lifting platform;

Fig. 7 is a partial diagrammatic elevation showing our apparatus as illustrated in Fig. 6 in a partially raised position; and

Fig. 8 is a partial diagrammatic elevation illustrating the position of our device with a release track top in position on the lifting platform.

Briefly, we accomplish the objects of our invention by providing four upright posts mounted for vertical reciprocation in the pit walls below the release track top. Means are provided for connecting the release track top to the posts, either permanently or releasably as required by circumstances. Our drop table includes a lifting platform carrying four laterally projecting stirrups spaced apart a distance equal to the spacing of the posts, whereby the stirrups can be aligned by movement of the drop table with laterally projecting lugs secured to the lower portions of the posts. Thus the drop table may be racked into position below the release track top and as the platform is raised the stirrups will engage the lugs on the posts, thus causing the posts to move upwardly carrying the release track top.

In some installations, particularly where remote control is to be employed, we provide means for preventing accidental nesting of the release track top on a service track top. This apparatus includes a lever arrangement carried by the platform and including an arm which actuates a lower limit switch, the latter being utilized to limit the downward movement of the lifting platform. If a service track top is in position on the lifting platform, the lever mechanism is actuated to raise the switch-engaging arm of the mechanism, thus permitting the platform to travel downwardly a greater distance than would be permitted if the lever were in unactuated position. When the lifting platform is permitted to fall to this position, the stirrups will be at a level below the lugs on the posts, whereby upward movement of the platform will elevate both the posts and the release track top. If, however, the service track top is not in position on the lifting platform, the switch-actuating arm of the lever system will be in a depressed position and therefore actuate the low level limit switch to stop the platform at an intermediate position wherein the stirrups on the lifting platform are above the level of the lugs on the posts. Elevation of the platform under such conditions will not actuate the posts and will permit the lifting

platform to engage the release track top, which may thereafter be lowered on the platform.

Automatic operation from a remote point is attained by suitably positioning limit switches which fix the position of the drop table on the track, and which limit upward and downward movement of the drop table lifting platform. When thus installed it is not necessary to assign one or more workmen to duty in the pit, thus effecting a substantial saving in labor. In addition, speed of operation is substantially increased over that possible by manual operation, and the number of mistakes occurring is substantially reduced, since improper operation is made virtually impossible.

In Figs. 1 and 2 we have illustrated a typical drop table installation, wherein a plurality of service tracks 10 extend over a drop table pit 11, the gap being bridged by service track tops 12 releasably held in position by engagement with the pit wall. Pit 11 extends transversely beneath the level of the tracks 10 and includes longitudinal walls 13 normally of concrete. Rails 14 extend along the bottom of the pit 11 and carry a drop table, generally designated 16. Preferably, body support members 17 are mounted at floor level near the service tracks 10 and are utilized to support the body of a railway vehicle while the trucks or axle assemblies are being lowered on one of the service tracks top 12. A release track 18 also extends across the pit 11, being bridged by a release track top 19. Frequently a tunnel 21 is formed below the release track and opens into the pit 11, serving as storage for reconditioned truck and axle assemblies.

The drop table 16 is basically conventional in design and includes a frame 22 to which rail wheels 23 are journaled. The frame 22 also carries four upwardly extending screw members 24 suitably interconnected by gears, and driven by a reversible motor 26 for raising and lowering a lifting platform 27, which engages the threads on the screws 24. The lifting platform 27 usually consists of beams 28 secured together to form a square or rectangular outline, and of such length and width to receive and support the release track top 19, and the service track tops 12.

The service track tops 12 are usually of greater depth than the release track top 19. For convenience we therefore provide legs 29 extending downwardly from the bottom of the release track in registry with the beams 28 a distance sufficient to make the overall depth of the release track 19 equal to the overall depth of the service track tops 12.

In the longitudinal walls 13 of the pit 11, immediately below the release track 18, we provide four channel-shaped, upwardly extending members 31, in which we mount a plurality of rollers 32 carried by opposed shafts 33 secured to the members 31. Posts 34, preferably in the form of H or I-beams, are fitted within the channel-shaped member in such manner as to be supported for sliding vertical movement by the rollers 32 and by engagement with the inner walls of the member 31. If desired, bearing blocks 36 may be secured to one or more of the faces of the posts 34 for engagement with the members 31. One of the surfaces of the posts 34 is approximately flush with the surface of the longitudinal walls 13.

Lugs 37 are fixed to the lower portions of the posts 34 and project outwardly into the pit at a predetermined level above the rails 14. Lips 39 are formed on the upper portions of the posts 34 for engagement with retractable bars 41 re-

reciprocally mounted on the release track top 19 and actuated by rods 42. Stirrups 43 are fixed to the lifting platform 27 of the drop table 16 and project laterally beyond the lifting platform towards the longitudinal walls 13 of the pit, being spaced apart a distance equal to the longitudinal distance between the posts 34, in such manner that they may be vertically aligned for engagement with the lugs 37 by movement of the drop table 16 along the tracks 14.

The drop table 16 is provided with an upper limit switch 44 in the path of the lifting platform 27 for limiting upward movement and a lower limit switch 46, the latter being disposed in the path of an arm 47 of a bell crank lever 50 pivotally mounted on the lifting platform 27. A weight 51 may be secured to the arm 47, the movement of which is limited by stops 49. The other arm 48 of the bell crank 50 normally projects laterally upwardly above the upper surface of the beams 28 of the platform 27, and is depressed by engagement with a top 12, when the stop is in position on the platform 27. When so depressed, the end of the arm 47 is raised, thus permitting the platform 27 to travel downwardly a greater distance before the end of the arm 47 actuates the limit switch 46. When in this position, the level of the stirrups 43 carried by the lifting platform 27 is below the level of the lugs 37 on the posts 34, with the result that the drop table 16 may be moved along the tracks 14 until the stirrups 43 and the lugs 37 are in vertical alignment. As shown in Fig. 6, raising the lifting platform 27 therefore engages the stirrups 43 with the lugs 37, causing the posts 34 to move upwardly. Since the release track top 19 is supported by the posts 34 through the bars 41, it may be seen that the release track top will be carried upwardly by the posts, permitting the service track top 12 to be raised to the level of the release track 18.

When there is no service track top on the lifting platform 27, the weight 51 forces the arm 48 upwardly, thus lowering the free end of the arm 47. When in such position, the limit switch 46 will be actuated to stop the lifting platform 27 at an intermediate level somewhat above the low level previously described. When the lifting platform 27 is in its intermediate position, the stirrups 43 are disposed at a level above the level of the lugs 37. The drop table 16 may therefore be moved into position below the release track top 19 and the platform 27 raised without movement of the posts 34. The legs 29 on the release track engage the platform 27, thus permitting the release track top 19 to be disengaged from the posts 34 by actuation of the locking bars 41 and lowered with the lifting platform. The arm 48, however, will not be actuated, since the posts 29 hold the body of the release track top 19 in an elevated position where it can not engage the arm 48.

From the foregoing it may be seen that whenever a service track top is carried by the lifting platform, the arm 47 will be actuated in such manner as to permit the lifting platform to drop to its lowest position. When in this position, the level of the stirrups 43 is below the level of the lugs 37 on the posts 34, with the result that any upward movement of the lifting platform 27, when it is below the release track top 19 will cause the posts 34 and the release track top 19 to be lifted with the lifting platform. If, in other words, the lifting platform 27 does not carry a service track top, the lifting platform will

be permitted to lower only to its intermediate position in which the level of the stirrups 43 is above the level of the lugs 37. Upward movement of the lifting platform beneath the release track top 19 may therefore be accomplished without movement of the posts 34 and the lifting platform brought into engagement with the release top 19. Unintentional nesting of the release track top on the service track top is thus rendered virtually impossible, and the necessity of manually placing heavy posts in position on the lifting platform is eliminated.

As previously indicated, there are many installations where it is desired to also raise the track top 19 when the lifting platform 27 of the drop table 16 is actuated from position beneath the release track top, regardless of whether or not there is a service track top in position on the platform 27. Under such circumstances it is obvious that the bell crank lever 50 may be eliminated under the conventional stop member provided for actuation of the low level limit switch 46. The stop member will of course be adjusted to stop downward movement of the platform 27 and at a point where the level of the stirrups 43 on the platform 27 is below the level of the lugs 37 on the posts 34. It is also possible under such circumstances to permanently secure the release track posts, although this is seldom desirable.

In compliance with R. S. 4888, we have described in detail a preferred embodiment of our invention; but since various of these details may be modified as required by circumstances, we do not wish to limit ourselves specifically to the form herein described except in so far as defined by the appended claims.

We claim:

1. Apparatus for use in connection with a drop pit of a type having an elongated pit extending transversely beneath a plurality of railway tracks and bridged by a service track top and release track top movable vertically for use in servicing railway vehicle trucks and the like comprising a drop table having a frame movable along rails on the bottom of the pit, a lifting platform on the frame, power means on the frame engaging the lifting platform for driving the platform up and down between an upper position and a lower position, upright posts disposed in the pit beneath the release track top and engageable therewith for lifting the top, means for reciprocally supporting the posts for movement upwardly and downwardly, and spaced opposed members fixed to the lifting platform and projecting laterally therefrom towards the posts for engagement therewith as the lifting platform is raised from its lower position beneath the release track top.

2. Apparatus for use in connection with a drop pit of a type having an elongated pit extending transversely beneath a plurality of railway tracks and bridged by a service track top and release track top movable vertically for use in servicing railway vehicle trucks and the like comprising a drop table having a frame movable along rails on the bottom of the pit, a lifting platform on the frame, power means on the frame engaging the lifting platform for driving the platform up and down between an upper position and a lower position, upright posts disposed in the pit beneath the release track top and engageable therewith for lifting the top, means for reciprocally supporting the posts, an inward projecting lug fixed to the lower portion of each of the posts and a plurality of outwardly projecting stirrups

fixed to the lifting platform and disposed thereon for registry beneath said lugs when the lifting platform is in its lower position below the release track top.

3. Apparatus for use in connection with a drop pit of the type having an elongated pit extending transversely beneath a plurality of railway tracks and bridged by a service track top and a release track top movable vertically for use in servicing railway vehicle trucks and the like comprising a drop table having a frame movable along rails on the bottom of the pit, a lifting platform on the frame, power means on the frame engaging the lifting platform for driving the platform up and down between an upper and lower position, spaced upright posts in the pit beneath the release track top, means for detachably securing the release track top to the upper portions of the posts, supports fixed to the pit wall and slidably engaging the posts, an inwardly projecting lug fixed to the lower portion of each of the posts and a plurality of outwardly projecting stirrups fixed to the lifting platform and disposed for registry beneath said lugs when the lifting platform is in its lower position below the release track top.

4. Apparatus for use in connection with a drop pit of the type having an elongated pit extending transversely beneath a plurality of railroad tracks and bridged by a service track top and a release track top movable vertically for use in servicing railway vehicle trucks and the like comprising a drop table having a frame movable along rails on the bottom of the pit, a lifting platform on the frame, power means on the frame engaging the lifting platform for driving the platform up and down between an upper, an intermediate and a lower position, upright posts disposed in the pit beneath the release track top and engageable therewith for lifting the top, means for reciprocally supporting the posts, and members secured to the lifting platform for lifting engagement with said posts, said members being so disposed and arranged as to prevent engagement with the posts except when the lifting platform is beneath the release track top and in its lower position.

5. Apparatus for use in connection with a drop pit of the type having an elongated pit extending transversely beneath a plurality of railway tracks and bridged by a service track top and a release track top movable vertically for use in servicing railway vehicle trucks and the like comprising a drop table having a frame movable along rails on the bottom of the pit, a lifting platform on the frame, power means on the frame engaging the lifting platform for driving the platform up and down between an upper and lower position, a limit switch for stopping downward movement of the table, a lever on the lifting platform having an arm in the path of the limit switch and movable from a first position to a second position only by a service track top on the platform, thereby positioning the platform in an intermediate position in the absence of a service track top and in its lower position when the service track top is carried by the platform, a plurality of upright posts supported below the release track top for lifting engagement therewith, each of said posts having an inwardly projecting lug near the lower end and a plurality of outwardly projecting stirrups fixed to the lifting platform for lifting engagement with the lugs only when the platform is raised

from said lower position beneath the release track top.

6. Apparatus for use in connection with a drop pit of the type having an elongated pit extending transversely beneath a plurality of railway tracks and bridged by a service track top and a release track top movable vertically for use in servicing railway vehicle trucks and the like comprising a drop table having a frame movable along rails on the bottom of the pit, a lifting platform on the frame, power means on the frame engaging the lifting platform for driving the platform up and down between an upper and lower position, a plurality of upright supports in the pit walls below the release track top, a post slidably mounted in each of the supports, means for detachably fastening the release track top on the posts, an inwardly projecting lug fixed to the lower portion of each of the posts, outwardly projecting stirrups fixed to the lifting platform and spaced for vertical registry with said lugs when the platform is positioned below the release track top, a low limit switch on the frame and a lever mechanism on the platform for actuating the limit switch and thereby restricting downward movement of the platform to an intermediate level or to said lower level of the platform, said levels being selected to dispose the stirrups above the lugs when the platform is at its intermediate level and below the lugs when the platform is at its lowest position, the lever mechanism being normally in position to permit movement of the platform to said intermediate position, said lever being moveable from such position by engagement of a service track top only on the platform.

7. Apparatus for use in connection with a drop pit of the type having an elongated pit extending transversely beneath a plurality of railway tracks and bridged by a service track top and a release track top movable vertically for use in servicing railway vehicle trucks and the like comprising a drop table having a frame movable along rails on the bottom of the pit, a lifting platform on the frame, power means on the frame and engaging the lifting platform for driving the platform up and down between an upper and lower position, a plurality of hollow upright supports in the pit walls below the release track top, a post slidably mounted in each of the supports, means for detachably fastening the release track top on the posts, an inwardly projecting lug fixed to the lower portion of each of the posts, outwardly projecting stirrups fixed to the lifting platform and spaced for vertical registry with said lugs when the platform is positioned below the release track top, a low limit switch on the frame and a lever mechanism on the platform for actuating the limit switch and thereby restricting downward movement of the platform at an intermediate level or at the lower level of said platform, said lever mechanism including a first arm pivotally secured to the platform and movable between two positions, both of said positions being in the path of the limit switch, and a second arm connected to the first arm and projecting upwardly beyond the surface of the platform for engagement with a service track top only carried thereby.

8. Apparatus for use in connection with a drop pit of a type having an elongated pit extending transversely beneath a plurality of railway tracks and bridged by a service track top and a release track top moveable vertically for use in servic-

ing railway vehicle trucks and the like comprising a drop table having a frame moveable along rails extending along the bottom of the pit, a lifting platform on the frame, power means on the frame engaging the lifting platform for driving the platform up and down between an upper position and a lower position, upright posts disposed in the pit beneath the release track top for engagement therewith for lifting said top, means for reciprocally supporting the posts and interengageable means on the lifting platform and on the posts for coupling the posts to the platform as the platform is raised from its lower position beneath the release track top.

9. Apparatus for use in connection with a drop pit of a type having an elongated pit extending transversely beneath a plurality of railway tracks and bridged by a service track top and a release track top moveable vertically for use in servicing railway vehicle trucks and the like comprising

20

ing a drop table having a frame moveable along rails extending along the bottom of the pit, a lifting platform on the frame, power means for driving the platform up and down between an upper position and a lower position, upright posts disposed in the pit beneath the release track top for engagement therewith for lifting said top, means for reciprocally supporting the posts and interengageable means on the lifting platform and on the posts for coupling the posts to the platform as the platform is raised from its lower position beneath the release track top.

LOUIS D. HOLMES.
